UNITED STATES PATENT OFFICE.

WIARD B. IHNEN, OF NEW YORK, N. Y.

DESIGN FOR A GALOSH.

Application filed December 15, 1926. Serial No. 20,058. Term of patent 3½ years.

To all whom it may concern:

Be it known that I, WIARD B. IHNEN, a citizen of the United States, residing at 74 Charles Street, borough of Manhattan, city, county, and State of New York, have invented a new, original, and ornamental Design for Galoshes, of which the following is a specification, reference being had to the accompanying drawing, forming part thereof.

The figure is a side elevation of a galosh showing my new design, the upper portion of which is made of colored oiled silk.

I claim:

The ornamental design for a galosh, as shown and described.

WIARD B. IHNEN.
